COMBINED FRAME AND HOLDER FOR MOUNTING X-RAY FILMS

Herman C. Spranger, 923 S. 48th St.,
Philadelphia, Pa. 19143

Filed May 26, 1969, Ser. No. 17,344

Term of patent 7 years

Int. Cl. D24—02

U.S. Cl. D83—1

FIG. I.

FIG. 2.

FIG. 3.

FIG. 4.

FIG. 5.

FIG. 6.

FIG. 7.

FIG. 1 is a perspective view of a combined frame and holder embodying the ornamental design of the present invention;

FIG. 2 is a front elevational view of the device shown in FIG. 1;

FIG. 3 is a right-hand side elevational view of the device;

FIG. 4 is a top plan view of the device;

FIG. 5 is a rear elevational view of the device;

FIG. 6 is a left-hand side elevational view of the device; and

FIG. 7 is a bottom plan view of the device.

I claim:

The ornamental design for a combined frame and holder for mounting X-ray films, substantially as shown.
